US00D631886S

(12) **United States Design Patent**
Vance et al.

(10) **Patent No.:** US D631,886 S
(45) **Date of Patent:** ** *Feb. 1, 2011

(54) **PORTION OF A DISPLAY SCREEN WITH A
USER INTERFACE**

(75) Inventors: **Michael Steffen Vance**, Kenmore, WA (US); **Jasdeep Singh Chugh**, Renton, WA (US); **Feridoon Malekzadeh**, Seattle, WA (US); **Valerie Lynn Goulart**, Seattle, WA (US); **Jared T. Benson**, Pleasant Hill, CA (US); **Christian Robertson**, Concord, CA (US); **Shilpa R. Shah**, Oakland, CA (US); **Gabriel J. White**, San Francisco, CA (US); **Joseph L. Ungari**, Seattle, WA (US)

(57) **CLAIM**

The ornamental design for a portion of a display screen with a user interface, as shown and described.

DESCRIPTION

The FIGURE is a front view of a portion of a display screen with a user interface showing the claimed design.

The portion of the display screen and the portions of the user interface illustrated in broken lines form no part of the claimed design.

1 Claim, 1 Drawing Sheet
